UNITED STATES PATENT OFFICE.

JOSEPH A. GRIMES, OF CENTRAL FALLS, AND FRANK M. BENEDICT, OF PAWTUCKET, RHODE ISLAND.

CARRIER FOR BRAIDING-MACHINES.

SPECIFICATION forming part of Letters Patent No. 668,329, dated February 19, 1901.

Application filed November 10, 1900. Serial No. 36,140. (No model.)

To all whom it may concern:

Be it known that we, JOSEPH A. GRIMES, a resident of Central Falls, and FRANK M. BENEDICT, a resident of Pawtucket, in the 5 State of Rhode Island, citizens of the United States of America, have invented certain new and useful Improvements in Carriers for Braiding-Machines, of which the following is a specification.

10 Our invention relates to improvements in carriers for braiding-machines in which the rotation of the bobbin is regulated by what is commonly known as a "top weight" provided with a dog or pawl which engages 15 notches in the upper head of the bobbin; and the purpose of our invention is to provide a carrier for braiding-machines in which the action of the top weight in regulating the revolution of the bobbin will be more prompt 20 and effective than by the devices now in use. We accomplish this purpose by the mechanism shown in the accompanying drawings, in which—

25 Figure 1 is a vertical side view of the carrier with its bobbin and the top and bottom weights, the top weight being in actual engagement with the notches in the upper head of the bobbin. Fig. 2 is a similar side view of the carrier, showing the top weight raised 30 out of engagement with the notched bobbin-head.

The same parts are designated by the same letters throughout both views.

In Fig. 1, A is the bobbin, shown in position upon the carrier, t being the thread, b 35 the top weight, b' the pawl or dog, engaging the notches in the head of the bobbin, c what is commonly known as the "bottom weight," and d the vertical arm, on which the top and bottom weights b and c slide.

The top of the dog b' is provided with notches b" and a thin spring a, adapted to fit closely into any one of these notches, according to the tension required, the other end of 45 a engaging the projection d' at the top of the member d of the carrier.

In carriers of the type referred to the weights b and c serve together as a tension-regulator. When more thread is demanded 50 by the draft of the braid, the bottom weight c is lifted until it comes in contact with the

top weight b, and the pull on the thread continuing the top weight b is lifted, thus releasing the pawl b' and permitting the bobbin A to revolve. Where the operation of 55 the machine is very rapid as the carrier in its revolution goes in and out, the pull upon the thread comes not steadily, but by a jerking motion in all the carriers now in use. As a result the bottom weight c is frequently 60 thrown with considerable violence against the top weight b, lifting it quite a distance above the bobbin-head. b, having its momentum to overcome and actuated only by its own weight, does not instantly return, and as a 65 result the bobbin A, instead of revolving through only a portion of a revolution, frequently makes an entire revolution suddenly, thus leaving a large amount of slack thread 70 which enables the bottom weight c to drop 75 the entire distance to the bottom of the slide d, thus automatically stopping the machine, inasmuch as the bottom weight c operates in machines of the type in question automatically to stop the machine when the thread breaks and the weight c is released. Various methods have been adopted to prevent the too-free revolution of the bobbin under conditions such as those described, but without much practical success. So far as we are 80 aware no means have been employed for securing the rapid return of the top weight b other than by its own weight.

Our invention consists of the spring a, above referred to, fastened at one end to the 85 pawl b' and at the other end to the member d just below its upper extremity d'. As shown in Fig. 2, when a sudden jerk of the thread lifts the bottom weight c, thus also lifting the top weight b, the spring a is compressed for an instant, but by its elasticity it instantly depresses the top weight b before the spool A has an opportunity to make more than that portion of a revolution represented by a single notch in the head, thus preventing 90 undue slackness of the thread, and thus preventing the unintentional stopping of the machine.

The tension of the spring a, as will be seen, may be regulated by the various notches b". 105 By means of this spring a very much more regular tension is given to the thread and

the unintentional stopping of the machine is prevented, and a very much greater speed may be obtained from the machine than is possible by the form of carriers of the type specified now in use.

It is evident that a spring made from either flat or round wire will work equally well and either may be used.

Having now described our invention, what we claim, and desire to secure by Letters Patent, is—

In a carrier for braiding-machines of the type shown, the combination of a top weight carrying a pawl adapted to engage the bobbin-head, said pawl having a plurality of

notches in the upper edge thereof; and a spring *a* fixed at its lower end in said pawl by means of said notches, and held in place at its upper end by the projecting lug *d'* of the member *d*, and operating to quickly depress the top weight when the same is raised, substantially as described. 20

Signed at Pawtucket, Rhode Island, this 6th day of November, 1900.

JOSEPH A. GRIMES.
FRANK M. BENEDICT.
